UNITED STATES PATENT OFFICE.

ASHTON G. STEVENSON, OF CHICAGO, ILLINOIS.

SLUG-CASTING MACHINE.

Original application filed January 29, 1921, Serial No. 441,077. Divided and this application filed October 27, 1923. Serial No. 671,133.

My invention relates to improvements in type slug casting machines, and has especial reference to machines which are commonly known as "linotype" or line casting machines.

In a machine of this kind, as commonly constructed, there is a mold wheel which carries several molds in which the slugs are cast and which is adapted to be rotated to position the several molds in various positions for the several operations of casting, ejecting, etc. Associated with the mold wheel are means for supporting the usual matrices for casting printing slugs or what is known as a quad block slide holder for casting borders or line printing slugs, etc., or blanks.

This present application is a division of my copending application Serial Number 441,077, filed January 29, 1921, and is directed particularly to the idea of the recessed slides in combination with the low mold for producing slugs of various heights from those which are equal in height to the thickness of the thin mold, I employ, viz., low quads or furniture, to the full height slugs and also to the means which I have devised for making it possible to practically use the low or thin mold in standard line casting machines of the linotype class.

In the printing art, different kinds of printing plates are made use of which owing to their method of manufacture have different thicknesses. For instance, stereotype plates are .159 of an inch in thickness; zinc plates .065 of an inch thick.

My novel low or thin mold is preferably about one eighth of an inch thinner than the standard thickness mold and by the use of quad block slides recessed, on their mold cooperating faces to suitable depths, I am enabled to produce foundations for these various printing plates on the otherwise standard linotype or line casting machines.

My invention will be more readily understood by reference to the accompanying drawings forming part of this specification and in which:

Figure 1, is a face view of a mold and wheel, the mold wheel being indicated in dotted lines;

Figure 2, is a vertical section of the mold on the line 2-2 of Figure 1 and showing associated parts of the machine;

Figures 3 to 5 inclusive, are sectional views showing different slides for use with

the low mold and the standard slide block; and

Figure 6, is a diagrammatic view illustrating the related heights of the several slugs produced.

In the so-called linotype machine a mold wheel 1 is provided, usually carrying four molds, similar to that shown at 2, on its face, said molds being equally circumferentially spaced thereon. Each mold consists of a base 3 rigidly secured to the web of the wheel usually by screws 4 and a removable cap 5 held in position by screws 6 projecting through the outer part or rim of the mold wheel. The cap is adjustable from and toward the base for providing a mold slot 7 between the base and cap of different heights or thicknesses for producing slugs of different thicknesses. The cap is spaced from the base by liners 8 and 9 at the ends of the slot 7.

Standard line casting machines as constructed are adapted to cast slugs of full printing height, viz., .918 inches in height from the printing face to the base of the slug. All but a very small part of such total height, viz., .043 of an inch is formed in the mold, the balance of .043 of an inch being formed in the matrices.

I purposely make the mold 2 of less depth from front to back than the standard mold preferably by about one-eighth of an inch, and in order to cast low quads or type furniture I provide a blank slide 10 for mounting in a standard quad block 11 see Figure 3. The slide 10 is thick enough to fill in between the quad block 11 and the adjacent face of the mold 2, the slide having a plane face 12 for closing the front of the mold slot 7. Obviously the slug 13 which would be cast in the mold slot would be equal in height to the thickness of the mold. Such low slugs are especially adapted for use as low quads or type furniture. This low quad is less than standard printing height by the reduction of the mold in thickness, viz, one-eighth of an inch plus the depth of the part of a printing slug produced in the matrix cavities, viz., .043 of an inch or about one-sixth of an inch.

Between this low quad height and the full printing height I produce quad or printer's slug material of any height desired by providing slides, similar to the extra thick slide 10 as shown at 14, Figure 4, and 15, Figure 110

5, that is of a thickness sufficient to properly fill in between the quad block 11 and the adjacent face of the mold and I provide the operating face of the slide with a recess, as 5 shown at 16, Figure 4, or at 17, Figure 5, of greater or less depth depending upon the height of slug material wanted.

The slide 14 with the shallow recess 16 in co-operation with the low mold 2 produces slugs 18 of a height suitable to be used 10 as foundation material for stereotype plates and the slide 15 with its deeper recess 17 in co-operation with the low mold 2 produces slugs 19 of a height suitable for use 15 as foundation material for zinc plates.

In Figure 6 I have illustrated diagrammatically the relation of the several different heights of slugs, the slug 20 representing a full height or printing slug.

20 It will now be understood that by use of extra thick slides recessed more or less, or with plane faces, I can produce slugs of any height desired from a low quad to practically a full height slug.

25 The mold, as already explained, is mounted on a mold wheel and the wheel is adapted to be rotated to carry the mold from the casting position, shown in full lines in Figure 1, to the slug ejecting position, shown in dotted lines, that is 90 degrees to the right from the casting position. In this position of the mold an ejector blade 20 is pushed into the mold slot from the rear to force the cast slug forwardly out of the mold. It

30 requires considerable pressure to push out the slug, and to prevent damage to the mold wheel and its related parts, the machine is provided with means for sustaining or receiving this thrust. This comprises a strong 35 vertically arranged frame 21 mounted at its lower end on a cross bar 22 forming part of the machine and braced or held at its upper end by a cross bar 23 clamped to the frame of the machine by clamping screws 24. This 40 frame 21 carries stops or abutments or banking pins 25 arranged to contact with the face of a mold of standard thickness, at the ends of the mold slot when the mold is in ejecting position, as shown in Figure 2.

45 As I have cut away the face of the mold substantially one-eighth of an inch below or back of standard position, standard thrust stops or banking pins, as they are known in the trade, would not reach the 50 face of the mold, and to make up the difference I provide plate or forwardly projecting parts 26 on the liners 8 and 9, and which are substantially one-eighth of an inch thick and build up or reproduce the face of the 55 original standard thickness mold at these 60 positions and arranged to contact with the banking pins 25.

The inner edge of the lower part 3 of a standard thickness mold operates upon a 65 suitable stop mechanism to regulate the

amount of the rotation of the mold wheel and to cause it to stop at certain predetermined points. In reducing the thickness of the mold, as described, this co-operation of the mold edge with the stop mechanism 70 is destroyed, and in order to reproduce this action I provide a forwardly extending projection 27 which is formed by securing a small plate 28 to the inner edge of the inner part 3 of the mold by a screw 29. This part 75 projects out from the reduced face of the mold, the amount the mold is thinner than a standard thickness mold and reproduces the original lower edge for a short distance so that it properly co-operates with the 80 standard stop mechanism.

As it is obvious that many modifications of my invention will readily suggest themselves to one skilled in the art, I do not limit or confine my invention to the specific details 85 of construction herein shown and described.

I claim:

1. In a machine of the kind described, a mold lower than a standard mold, a quad block arranged in front of the mold and 90 positioned therefrom farther than usual by substantially the reduction in height of the mold below standard, a slide associated with the quad block adapted to fill in between the block and the face of the mold, said slide having a mold depression in its face adapted to extend the mold cavity forward and to cast a slug of less than full height and higher than the height of a mold.

2. In a machine of the kind described, a mold lower than the standard mold, a quad block arranged in front of the mold and positioned therefrom farther than usual by substantially the reduction of the mold in 95 height below standard, a quad slide carried by the block and of a thickness to fill in between the block and the mold, said slide having a depression in its mold face for extending the mold cavity forward, and forwardly extending projections on the mold 100 face at the ends of the mold slot equal in depth to the reduction of the mold in height for co-operation with the standard banking pins when the mold is positioned for ejecting 105 the slug.

3. In a machine of the kind described, a mold which is lower than the standard mold in height, a quad block arranged in its standard position in front of the mold, its mold-opposing face spaced from the face 110 of the mold farther than usual by an amount equal to the reduction of the mold in height below standard, a quad slide carried by the block and of a thickness to fill in between the block and the mold and provided in its face with a depression for carrying the mold cavity forward, blocks on the mold face at the ends of the mold slot thick enough to contact with the standard banking pins 115 when the mold is positioned for ejecting 120 the slug.

4. In a machine of the kind described, a standard thickness mold, a quad block arranged in its standard position in front of the mold, its mold-opposing face spaced from the face 125 of the mold farther than usual by an amount equal to the reduction of the mold in height below standard, a quad slide carried by the block and of a thickness to fill in between the block and the mold and provided in its face with a depression for carrying the mold cavity forward, blocks on the mold face at the ends of the mold slot thick enough to contact with the standard banking pins 130 when the mold is positioned for ejecting the slug.

the slug, and a projection on the inner edge of the base of the low mold for co-operation with the standard mold stop mechanism.

4. In a machine of the kind described, a mold lower than the standard mold, a quad block arranged in front of the mold and positioned therefrom substantially the distance of the reduction of the mold in height below the standard, a quad slide carried by the block and of a thickness to fill in between the block and the mold, said slide having a depression in its mold face for extending the mold cavity forward, liners between the base and the cap of the mold and projections on the forward edges of the liners adapted for co-operation with the standard banking pins during ejection of a slug from the mold slot.
5. In a machine of the kind described, a mold thinner than the standard mold, a quad block adapted to be positioned in front of the mold and spaced therefrom, a distance which is greater than the usual distance by the amount the mold is thinner than usual,

a series of slides interchangeably mountable 25 on the block, each slide being adapted to close the slot of the mold, and said series having recesses of different depths for producing, in co-operation with the mold, a series of slugs or bases of like different 30 heights, and all thereof intermediate in height between the low mold thickness and full printing height.

6. In a machine of the kind described, a slug mold of less than standard thickness 35 and a standard quad block in combination with a slide bar for mounting on the block and thick enough to retain the mold and quad block in standard relative positions when the machine operates to close the mold 40 and a recess in the slide of a depth less than the thickness of the slide for extending the mold cavity forward to produce printers' slug material of greater height than the thickness of the mold. 45

Signed at Washington, District of Columbia, this 27th day of October, 1923.

ASHTON G. STEVENSON.
